UNITED STATES PATENT OFFICE

FRANK E. BOWERS, OF DREXEL HILL, PENNSYLVANIA, ASSIGNOR TO WALL & OEHLS, INCORPORATED, OF PHILADELPHIA, PENNSYLVANIA, A CORPORATION OF PENNSYLVANIA

DESIGN FOR AN OPHTHALMIC MOUNTING

Application filed November 16, 1931. Serial No. 41,745. Term of patent 14 years.

To all whom it may concern:

Be it known that I, FRANK E. BOWERS, a citizen of the United States, residing in Drexel Hill, county of Delaware, State of Pennsylvania, have invented a new, original, and ornamental Design for an Ophthalmic Mounting, of which the following is a specification, reference being had to the accompanying drawing, forming part hereof.

Fig. 1 is a view in front elevation of an

ophthalmic mounting showing my new design; and

Fig. 2 is a view in top plan of the same.

I claim:

The ornamental design for an ophthalmic mounting, substantially as shown.

In testimony whereof I have hereunto signed my name this 13th day of November, A. D. 1931.

FRANK E. BOWERS.
